UNITED STATES PATENT OFFICE.

GEORGE WHITNEY BELL, OF EL MORO, COLORADO.

CUFF-HOLDER.

SPECIFICATION forming part of Letters Patent No. 423,722, dated March 18, 1890.

Application filed December 2, 1889. Serial No. 332,249. (No model.)

To all whom it may concern:

Be it known that I, GEORGE WHITNEY BELL, of El Moro, in the county of Las Animas and State of Colorado, have invented certain new and useful Improvements in Cuff-Holders; and I do hereby declare that the following is a full, clear, and exact description of the invention, which will enable others skilled in the art to which it appertains to make and use the same, reference being had to the accompanying drawings, and to the letters of reference marked thereon, which form part of this specification.

This invention relates to certain improvements in cuff-holders; and the invention consists in certain novel features of construction and in combinations of parts more fully and particularly set forth hereinafter.

Referring to the accompanying drawings, Figure 1 is a section of the holder in operation, showing portion of a cuff in longitudinal section. Fig. 2 is a detail perspective of the holder, showing the cuff-button detached.

In the drawings, the reference-letter *a* indicates a cuff.

h indicates the cuff-button, having a straight shank *i*, provided with a transverse slot or opening *c*.

The holder consists of the elongated body or bar *b*, preferably tapered at its outer end to readily enter the slotted shank of the cuff-button. At its inner end the body is provided with the spring clamp or catch *k*, pivoted thereto to tightly engage the shirt-sleeve and lock the cuff thereto. Within its length the body *b* is provided with a lateral arm *d*, to extend through the two inner button-holes of the cuff. The upper portion of this arm is provided with a lateral slot *f*, partially closed at its open end by a depending tongue or lip *g*. A spring arm or tongue *e* is secured, preferably pivoted, at one end to the body *b* near the inner end thereof, so that its free end can be slipped laterally into the slot *f* and be held therein by the lip *g*.

In operation the body *b* is slipped longitudinally into the inner end of the cuff, with its outer tapered end extending through the slotted shank of the cuff-button. The lateral arm *d* is then slipped through the inner button-holes, and the spring-tongue *e*, extending over the exterior of the inner end of the cuff, is slipped into the slot *f* of the arm *d*, thereby holding said arm from slipping out of the button-holes and forming a catch to retain the arm in said holes.

The extreme simplicity and many advantages of this holder are obvious. The wear, tear, and trouble of passing buttons through hard stiff cuffs are avoided.

What I claim is—

1. A cuff-holder consisting of the elongated flat body formed at its outer end to engage and hold the cuff-button shank, the slotted lateral arm projecting from its body within its length, the laterally - swinging spring-tongue pivoted at one end to the body, with its free end adapted to engage said slotted arm, and a clamp pivoted to the inner end of the body to grip the shirt-sleeve, substantially as described.

2. The combination, with the cuff-button having a slotted shank, of an elongated rigid body formed at its outer end to enter said shank, a lateral arm projecting from the body between its ends to pass through the rear cuff-button holes, a laterally-swinging spring-tongue pivoted to the inner end of the body to allow its free end to lock on the outer end of said arm, and means on the inner end of said body to secure the same to the shirt-sleeve, substantially as described.

In testimony that I claim the foregoing as my own I affix my signature in presence of two witnesses.

GEORGE WHITNEY BELL.

Witnesses:

J. P. DETAMORE,
WM. ARNETT.
